CLAIM

The ornamental design for a package for a medical device, as shown and described.

DESCRIPTION

FIG. 1 is a top perspective view of a package for a medical device showing our new design;

FIG. 2 is a front perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.
